HYDRAULIC JACK

Herbert P. Brumder, Chenequa, Wis., assignor to
 Blackhawk Mfg. Co., Milwaukee, Wis., a corporation of Wisconsin

Application August 15, 1938, Serial No. 224,881

3 Claims. (Cl. 60—52)

My invention relates generally to improvements in the construction of hydraulic jacks, and has for its principal object, the provision of a simplified jack assemblage which is highly efficient in operation.

Hydraulic jacks are old and well known, and are now being used extensively in the automobile industry especially for the purpose of elevating such vehicles in order to permit removal of the wheels or the like. In an effort to produce durable jacks at moderate cost, the manufacturers of some of these devices have heretofore resorted to die-casting in the construction of the major parts, and in order to obtain a compact assemblage some of these jacks are formed with the liquid supply reservoir surrounding the plunger barrel and with the pump cylinder and piston detachably associated directly with the base of the jack and disposed at an oblique angle relative to the axis of movement of the jack plunger. The hydraulic jacks of this latter type have proven quite satisfactory in use, but rather tedious to construct by the die-casting method because some of the valves and numerous ports were located within the relatively large and bulky base casting, and the rather delicate valve seats and liquid passages were difficult to form and to machine. The manufacturers of these jacks were therefore confronted with many difficulties in quantity production, and in the production of high grade jack units which could be sold at moderate cost and would remain effective in use.

It is therefore a more specific object of my present invention to provide an extremely simple, compact and durable hydraulic jack assemblage which can be readily manufactured, and wherein the ports and valve seats may be easily formed and are conveniently accessible for inspection.

In accordance with the present improvement, the jack barrel and the liquid supply reservoir surrounding the barrel, are formed integral with the base and are connectible with each other for the transfer of liquid from the reservoir to the barrel and vice versa, through a single relatively large and easily formed passage. The valves and the relatively smaller suction, discharge and by-pass ports of my improved jacks are all disposed within a rather simple pump casing which is detachably secured to the base in open communication with the reservoir and with the single large passage in the base casting. Thus, aside from facilitating manufacture of the assemblage, the control valves are made more readily accessible by mere removal of the pump from the base, and the entire jack is less apt to become ineffective

due to clogging of liquid passages or escape of actuating liquid.

A clear conception of an embodiment of my present invention, and of the manner of constructing and of utilizing a hydraulic jack built in accordance with my improvement, may be had by referring to the drawing accompanying and forming a part of this specification wherein like reference characters designate the same or similar parts in the several views.

Fig. 1 is a part sectional side elevation of one of my improved hydraulic jacks, the section being taken centrally through the pump and valve assembly; and

Fig. 2 is a transverse horizontal section through the jack of Fig. 1, taken along the line 2—2.

Although I have shown and described my invention herein as being specifically applied to a hydraulically actuated automobile jack, it is not my intention to thereby unnecessarily restrict the scope and utility of the improved features.

Referring to the drawing, the improved hydraulic jack assemblage shown therein comprises in general a main support or base 5 having a plunger barrel 6 and a liquid reservoir forming wall 7 formed integral with the base and projecting upwardly therefrom; a plunger 8 movable approximately vertically within the barrel 6 and having a cup-shaped flexible seal 9 at its lower end coacting with the bore 10 of the barrel; a closure cap 11 detachably secured to the wall 7 and enclosing the top of the liquid supply chamber or reservoir 12, and coacting with the plunger 8 to guide the same; a pump casing or cylinder 13 detachably secured to the base 5 and having a central bore 14 which is communicable through ports 15, 16 with the reservoir 12 and with the barrel bore 10, respectively; a relatively large single passage 17 formed in the base 5 in axial alignment with the cylinder 13 and directly connecting the lower extremity of the bore 10 with an enlarged lower portion 18 of the pump discharge port 16; a by-pass duct 19 formed in the cylinder casing 13 and connecting the port portion 18 with the reservoir 12, and having therein a manually manipulable relief valve 20; a pump piston 21 reciprocable within the casing bore 14; and an operating lever 22 pivotally suspended from the base 5 and wall 7 by means of a fulcrum pin 23, and coacting through a transverse pin 24 with a notch in the upper portion of the piston 21.

The base 5, barrel 6 and wall 7, are preferably formed of suitable metal by die-casting, in a well known manner, and the bore 10 and annular

reservoir chamber 12 are therefore preferably disposed concentric with respect to a common vertical axis, while the passage 17 and the space within which the cylinder 13 is normally confined are likewise preferably disposed concentric with respect to another common obliquely inclined axis. The bore 10 is truly cylindrical, but the bounding surfaces of the reservoir may be slightly tapered so as to permit free withdrawal of the mold forming elements, and the upper portion of the bore 10 is in open communication with the reservoir chamber 12 through one or more openings 25. The cup-seal 9 may be clamped to a disk 26 coacting with the lower end of the plunger 8, by means of a nut 27; and the upper extremity of the plunger 8 is provided with an adjustable screw head 28 of usual construction. The detachable upper closure cap 11 is adapted to coact with the head 28 as shown in Fig. 1, when the latter is in lowermost position, and this cap 11 may be provided with suitable packing 29 coacting with the plunger 8. The outer wall 7 may be provided with integral ears 30 in which the pivot pin 23 is mounted and which also reinforce the inclined socket 31 within which the cylinder casing 13 is confined, and this wall 7 may also be connected to the base 5 by reenforcing ribs 32 likewise formed integral with these elements.

The cylinder casing 13 within which all of the control valves are confined, may also be formed as a die-casting, and is confined within the socket 31 with its medial portion completely surrounded by liquid in the supply reservoir 12. The pump casing 13 is provided at its lower end with a reduced portion 33 snugly fitting a counter-bore in the base 5, and with a plane lower end surface coacting with an adjacent surface of the base casting; and the upper end portion 34 of the casing 13 is of enlarged diameter and snugly fits the bore of the socket 31. The cylinder casing 13 is normally detachably clamped in position by means of a ring nut 35, and the piston 21 which is slidable within the bore 14 of the casing 13, is embraced by a packing 36 and a packing retainer nut 37 which prevent escape 45 of liquid along the piston. As previously indicated, the piston 21 is reciprocable by means of the pin 24 carried by the lever socket 22, and a handle 38 may be secured to this socket and constitutes a part of the actuating lever. The lower end of the piston 21 is also provided with a cup shaped seal 39 which cooperates with the packing 36 to prevent leakage.

The pump discharge port 16 which connects the pump bore 14 with the large base passage 17, has a ball discharge valve 40 confined therein above the by-pass port 19, by means of a spring or snap ring in a well known manner; and the pump inlet or suction port 15 which directly connects the pump bore 14 with the reservoir 12, has a ball suction valve 41 confined therein by a similar snap ring. While the discharge port 16 is rectilinear throughout its entire length, the suction port 15 is preferably formed of two relatively inclined sections one of which is parallel to the bore 14, and the other of which is approximately parallel to the by-pass port 19, so as to permit convenient formation of all of the ports 15, 16, 18, 19 by die-casting operations. The ball by-pass valve 20 which is also confined within the cylinder casing 13 and is removable therewith, is adapted to be pressed against its seating to close the port 19 when the pump is being operated, by means of a spindle 42 having screw thread coaction with a threaded element 43, and

which is adapted to be manipulated from the exterior of the jack through handles 44. The spindle 42 is embraced by a packing 45 which is retained in place by the element 43, and when the pump is inactive and the spindle 42 is manipulated to release the by-pass valve 20 liquid subjected to pressure within the bore 10 and passage 17 will be quickly relieved of such pressure by the escape of excess liquid through the ports 18, 19 to the reservoir 12. In order to properly position the port 19 and the by-pass valve 20 relative to the spindle 42 when the cylinder casing 13 is placed within the socket 31, the cylinder casing 13 may be provided with a recess adapted to coact with a key 46 formed integral with the base 5, as shown in Figs. 1 and 2, and this key 46 will positively prevent rotation of the pump cylinder.

During normal use of my improved jack assemblage, the reservoir chamber 12 and the other confined spaces of the jack are supplied with liquid as shown in Fig. 1, and when the plunger 8 is in lowermost position, the by-pass valve 20 would ordinarily be closed. The lever handle 38 may then be oscillated to reciprocate the pump piston 21, and as this piston is elevated, liquid will be withdrawn from the supply chamber 12 through the port 15 and past the suction valve 41 into the pump bore 14 beneath the piston 21. When the piston 21 is subsequently forced downwardly, the liquid in the pump displacement chamber will be forced through the discharge port 16 past the delivery valve 40 and through the passage 17 into the bore 10 beneath the plunger cup seal 9, thus causing the plunger 8 to rise. Repeated reciprocation of the pump piston 21 will obviously cause the plunger 8 to rise higher and higher, until the seal 9 passes the relief opening 25, whereupon the plunger movement will automatically cease and excess liquid will escape from the bore 10 to the supply chamber 12. If reciprocation of the pump piston 21 should be discontinued, and the by-pass valve 20 should be released by withdrawal of the spindle 42, the pressure exerted by the plunger 8 upon the liquid which is confined within the bore 10, will then cause the liquid to flow through the passage 17, port portion 18, and port 19 past the valve 20, to the supply chamber 12, until the valve 20 is again sealed by manipulation of the spindle 42.

From the foregoing detailed description it will be apparent that the present invention provides an extremely simple, compact and durable jack assemblage which can be readily constructed and which is moreover conveniently manipulable. The major parts of the improved jack may obviously be effectively produced by die-casting because of the fact that the base 5 has no complicated and unduly restricted ports and passages therein, and further because of the fact that all of the relatively small ports as well as all of the valves are confined directly within the pump casing 13. This pump cylinder casing is readily removable from the confining socket 31 together with the valves 20, 40, 41, and the relatively small ports in the pump casing will likewise permit convenient manufacture of this casing by die-casting. The improved assemblage embodies no ports or passages which are not freely accessible at all times for inspection and cleaning, and proper assembly of the pump and base is obviously facilitated by the provision of the key 46 for insuring proper alignment of the spindle 42 with the by-pass valve 20. The improved jack assemblage may moreover be maintained tight

and free from leakage. The single enlarged passage 17 formed in the base 5 and which provides a common pump discharge and by-pass passage moreover eliminates possibility of undesirable leakage from the pressure chamber beneath the plunger 8, such as frequently occurs with former structures of this general type. By confining all of the control valves within the pump casing 13 which is detachable from the main jack and base casting 5, the pump parts may be manufactured independently of the jack parts, and all of the parts may be quickly assembled to complete the structure. All of the elements of the improved jack may obviously be readily formed and machined, and an abundant supply of liquid from the reservoir 12 to the pump and to the jack is constantly available.

It should be understood that it is not desired to limit this invention to the exact details of construction or to the precise mode of operation, herein shown and described, for various modifications within the scope of the claims may occur to persons skilled in the art.

I claim:

1. A jack comprising, an upwardly extending plunger barrel and an annular reservoir formed integral with and surrounding said barrel, said barrel and reservoir having an inclined upwardly open socket in open communication at its medial portion with said reservoir and the lower end of which communicates directly with the lower extremity of said barrel through a large passage formed concentric with the socket, a pump cylinder having opposite ends slip fitted within the lower and upper ends of said socket and being provided with a central piston bore, one side of the bottom of said piston bore being connected with said concentric passage by a rectilinear port having a discharge valve therein and the other side of said bottom being connected to said reservoir by an angular port having a suction valve therein while the portion of said rectilinear port between said discharge valve and said passage communicates through an outwardly directed by-pass port having a by-pass valve therein directly with said reservoir, all of said ports being formed wholly within said cylinder and lying in a common plane, and means operable from the exterior of said reservoir for manipulating said by-pass valve.

2. A jack comprising, an upwardly extending plunger barrel and an annular reservoir formed integral with and surrounding said barrel, said barrel and reservoir having an inclined upwardly open socket in open communication at its medial portion with said reservoir and the lower end

of which communicates directly with the lower extremity of said barrel through a large rectilinear passage formed concentric with the socket, a pump cylinder having opposite ends fitted within the lower and upper ends respectively of said socket and being provided with a central piston bore, one side of the bottom of said piston bore being connected with said concentric passage by a rectilinear port having a discharge valve therein and the other side of said bottom being connected to said reservoir by an angular port having a suction valve therein while the portion of said rectilinear port between said discharge valve and said passage communicates through an outwardly directed by-pass port having a by-pass valve therein directly with said reservoir, all of said ports being formed wholly within said cylinder and lying in a common plane, means for positively preventing rotation of said cylinder about its own axis when disposed within said socket, and a spindle movable from the exterior of said reservoir in axial alignment with said by-pass valve port for manipulating said by-pass valve.

25 3. A jack comprising, an upwardly extending plunger barrel surrounded by an annular reservoir formed integral with said barrel, said barrel and reservoir having an inclined upwardly open socket in open communication at its medial portion with said reservoir and the lower end of which communicates directly with the lower extremity of said barrel through a large rectilinear passage formed concentric with the socket, a pump cylinder having lower and upper ends slip fitted within the lower and upper ends respectively of said socket and being provided with a central piston bore, one side of the bottom of said piston bore being connected with said concentric passage by a rectilinear port having a discharge valve therein and the other side of said bottom being connected to said reservoir by an angular port having a suction valve therein while the portion of said rectilinear port between said discharge valve and said passage communicates outwardly directly with said reservoir through a by-pass port having a by-pass valve therein, all of said valves being of similar construction and said valves and ports being disposed wholly within said cylinder and lying in a common plane, means for positioning said pump cylinder with said plane disposed approximately radially of said plunger barrel and means movable through the wall of said reservoir in said plane for manipulating said by-pass valve.
